UNITED STATES PATENT OFFICE.

ERNEST H. WOELFFEL, OF POINT PLEASANT, WEST VIRGINIA.

CORNER RISER FOR BEDSPRINGS.

Application filed April 1, 1922. Serial No. 548,705.

To all whom it may concern:

Be it known that I, ERNEST H. WOELFFEL, a citizen of the United States, residing at Point Pleasant, in the county of Mason and State of West Virginia, have invented a new and useful Corner Riser for Bedsprings, of which the following is a specification.

This invention relates to a corner riser for bed springs, one of its objects being to provide a means whereby the end rails of the mattress frame can be securely fastened to the risers without requiring the use of rivets such as commonly employed.

Another object is to provide a snap fastening means which will hold the parts together securely and rigidly, it being possible to assemble the parts quickly.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

Figure 1 is an elevation of a corner riser and showing a portion of an end rail in position thereon.

Figure 2 is a plan view of the structure shown in Figure 1.

Figure 3 is a section on line 3—3, Figure 1.

Figure 4 is an elevation of a modified form of riser, a portion of an end rail being in position thereon.

Figure 5 is a section on line 5—5, Figure 4.

Figure 6 is a vertical section through another form of riser and the end rail engaged thereby.

Figure 7 is a section on line 7—7, Fig. 6.

Referring to the figures by characters of reference 1 designates the body portion of the riser preferably in the form of an open frame as shown in Figure 1, this riser being provided at one corner with a socket 2 for receiving one of the side rails of the mattress frame. Extending upwardly from opposite edge portions of the body 1 are fingers 3 and 4, the finger 3 being provided, along its top edge with an abutment 5 in the form of

a bead or flange. The upper ends of both of the fingers are straight and constitute rests for the top portion 6 of an angle strip 7 constituting the end rail of the mattress frame. 60 The outer edges of the fingers 3 and 4 are also straight so as to constitute bearings for the rail 7 and the rib or flange 5 is extended downwardly along the outer edge of the finger 3 so as to form an abutment for the depending portion of the end rail.

Extending from the body 1 of the riser between the fingers 3 and 4 is an intermediate finger 8 offset outwardly from the plane of the outer edges of the fingers 3 and 4 so as to allow the depending portion of the end rail 7 to fit snugly between said finger 8 and the fingers 3 and 4. Finger 8 has a beveled stud 9 on its inner face constituting a snap fastener element and an opening 10 is 70 formed in the depending portion of the rail 7 in such position that when said rail is abutting against the rib or flange 5 and is forced downwardly between the fingers as shown in Figures 1, 2 and 3, the stud 9 will 75 snap into the opening 10 and thus lock the riser and the end rail together securely.

Obviously by providing at each corner of the mattress frame a riser such as has been described, the end rails can be quickly assembled therewith without the use of rivets, bolts or the like and the parts will be held against relative movement so as to form a rigid structure.

Instead of forming the opening 10 in the 90 end rail and providing a stud on the intermediate finger, the structure can be varied as shown in Figures 4 and 5 wherein the riser 11 has an opening 12 in the intermediate finger 13 and a lip 14 is struck from the depending portion of the angular end rail 15. This lip is so located that when the end rail is resting on the fingers 16 and 17 and is abutting against the rib or flange 18 the lip 14 will project into the opening 12 and hold 100 the parts securely assembled. The assembly of the parts is effected simply by driving the angular end rail into position between the fingers.

Another modification of the structure shown in Figure 4 has been illustrated in Figures 6 and 7. In this form of device the side finger 25 having the flange or rib 26 constituting an abutment for the end rail 27 is provided with a beveled stud 28 and the intermediate finger 29 has a top retaining rib or flange 30. Thus the end rail 27 can

be inserted longitudinally between the fingers and under the flange 30 until it comes against the abutment 26 whereupon the beveled stud 28 will snap into an opening 31 formed in the end rail.

By providing risers such as have been described the number of operations necessary to produce a complete mattress spring are materially reduced because of the absence **10** of rivets, bolts or the like and, consequently, the cost of making such a frame is likewise reduced.

What is claimed is:—

15 The combination with the end rail of a mattress frame or the like, of a riser includ-

ing spaced upstanding means constituting separate bearings for the end rail, a finger opposite the space between said upstanding means, a portion of the rail being insertible between said means and the finger, and co-
operating snap fastening means upon the rail and riser for fastening the rail fixedly upon the spaced upstanding means.

In testimony that I claim the foregoing as my own, I have hereto affixed my signature **25** in the presence of two witnesses.

ERNEST H. WOELFFEL.
